UNITED STATES PATENT OFFICE.

ERNEST KOHLER, OF ALAMEDA, CALIFORNIA.

TORPEDO CAPTURING AND DESTROYING NET.

1,337,920.

Specification of Letters Patent. Patented Apr. 20, 1920.

Application filed October 17, 1919. Serial No. 331,402.

To all whom it may concern:

Be it known that I, ERNEST KOHLER, a citizen of the United States, and resident of the city of Alameda, in the county of Alameda and State of California, have invented a new and Improved Torpedo Capturing and Destroying Net, of which the following is a full, clear, and exact description.

10 The present invention relates to a net for capturing and destroying torpedoes and other propelled submarine vessels and has reference more particularly to a net which may be cast from a ship and vertically presented in the path of an approaching torpedo to intercept the torpedo in its travel toward the vessel from which the net is cast. As heretofore practised in naval warfare, various means have been provided for protecting ships against torpedo attacks. Most of these devices while found to be practical in protecting ships anchored in harbors are lacking in utility so far as concerns ships that are under way.

15 25 The present invention has for its primary object to provide a guard against submarine attacks which often occur at sea where the vessel is under way from one port to another.

20 A further object is to so construct the guard or protecting device that it will not only prevent the torpedo from reaching its goal, but the device is capable of also destroying the torpedo.

25 35 A practical embodiment of the idea is shown in the accompanying drawings in which—

30 Figure 1 is a side view of a net which is employed as a part of the invention, the said view showing the net as anchored to the winding drum and the projectiles.

35 40 Fig. 2 is a side elevation of the relative position of the net when presented in the path of the torpedo, the dotted lines showing the result of the torpedo striking the net just before the explosive charge of the projectile has been fired.

45 Fig. 3 is a side view of the winding drum showing the same partly in section.

50 Fig. 4 is a top plan view of the means for casting the projectiles showing its position relative to the drum on which the net is wound.

55 Fig. 5 is an end view in elevation looking in the direction of the arrows shown in Fig. 4.

Fig. 6 is an elevation of the pivotal mounting for the casting device.

Fig. 7 is a vertical section on the line 7—7 of Fig. 6.

Fig. 8 is a longitudinal section through one of the projectiles; and

Fig. 9 is a view in elevation of one of the projectiles showing the foldable canopy open and the firing mechanism cocked.

Referring to the drawings in detail, certain features of the idea consist in casting the net 1 into the path of an approaching torpedo such as A and intercepting the same in its travel toward the ship from which the net 1 is cast. The net 1 is anchored to and wound upon a relatively long floating drum 2 which drum is supported longitudinally along the gunwale or in any other convenient position on a ship with the spindles 3 at its opposite ends supported with freedom of rotation in suitable open bearings 4. The edge of the net may be anchored to the winding drum in any suitable manner such as by means of eyes 5.

The net is preferably constructed of heavy mesh material with the meshes thereof of proper size to insnare the tapered head of a torpedo. Secured to and spaced at proper intervals along the free end of the net are a plurality of projectiles 6 the particular construction of which will be presently described.

These projectiles primarily act in the capacity of casting weights whereby the net may be cast from the ship and as stated presented vertically in the path of an approaching torpedo. In order to effect the casting of the net in proper position to intercept the torpedo, the projectiles are simultaneously and collectively projected by means of a plurality of cannons 7, each of which is mounted with the bore thereof made to receive the cylindrical end 8 of a projectile. The cannons are adapted to be fired simultaneously and to accomplish this result an electric circuit which is controlled by a button 9 is employed. Upon closing of the circuit by this button 9, the circuit is completed to the firing device of each cannon and said cannons will be fired simultaneously. As stated the drum on which the net is wound is located along the side of the ship and the cannons which fire the projectiles 6 are arranged at spaced intervals over the net by means of a rotatable mounting 10 supported

intermediate its ends by a rotatable standard 11. Inasmuch as the bearings 4 for the spindle 3 of the drums are carried by the rotatable mounting 10 for the cannons, the 5 whole device is capable of longitudinal and vertical axial movement which will enable the device to be sighted by means of the handles 12. The standard 11 is provided with horizontal bearing 13 through which the 10 mounting 10 extends with freedom of rotation. This will enable vertical axial movement of the device to be had and inasmuch as the standard 11 is constructed of a post 14 on which the elongated sleeve 15 of the bearing 15 13 is mounted the necessary longitudinal axial movement of the device is obtained.

Each of the projectiles as stated is secured to the free end of the net 1 preferably by the eyes 16 and when the projectiles are 20 cast from the cannon 7, their weight will enable the net to be impelled a sufficient distance from the ship and presented vertically in the path of the approaching torpedo, see for instance Fig. 2. It is to be understood 25 that the drum 2 acts as a float, and that the whole device in the preferred embodiment of the arrangement is cast from the ship. If desirable, a line may be attached to the drum to recover the net or any part thereof or 30 instead of casting the complete device the drum may be more or less permanently secured in its bearings and act as a means for anchoring the net to the ship.

As heretofore described the projectiles 35 primarily involve the means for casting the net. They also have a secondary function. For instance it is not only desirable to capture the torpedo but if possible, the torpedo should be destroyed to prevent any possibility 40 of the same reaching its goal. With this in view, each of the projectiles is adapted to contain an explosive charge which will be fired by the impact of the torpedo with the net. To accomplish this, each projectile 45 is constructed with the explosive charge containing chamber 17, a removable head 18, a primer 19, a percussion cap 20, and a plunger 21 having a recess 22 adapted to normally overlie and house the percussion cap 20, the plunger being maintained in this position by the thumb screw 23 entering the side of the plunger casing 24 behind the plunger and by means of the transversely presented end 25 of one of the ribs 26, entering a recess in the side of the plunger 50 through a registering opening in the side of the plunger casing 24 in the rear of screw 23. This means will normally maintain the plunger inactive, and previous to firing the projectiles both of these means are withdrawn from engagement with the plunger whereby the same may be rendered capable 55 of longitudinal movement within its housing 24. Interposed between the plunger 21 and the end closure 28 of the casing 24 is a

coil spring 29, the tendency of which is to push the plunger toward the percussion cap 20. As stated when previous to firing the projectiles, the plunger is released, when the projectiles are submerged the canopy 27 will open, the folding ribs 20 permitting the same to move in this position, and the weight of the projectile will cause the plunger to recede to the rear of its casing 24, the projectile being secured to the net by the eye 16 which is fixed upon the plunger rod. Just as soon as the plunger has been withdrawn from around the percussion cap 20 an impaling finger 31 which is pivoted as at 32 and under the influence of the spring 33, 80 will contact with the percussion cap 20 and bridge the space between the edges of the recess 22 in the plunger so that impact of the plunger thereon may fire the charge in the chamber 17 through the percussion cap 20 and the primer 19. The firing of the charge is brought about in this manner. When a torpedo is in contact with the net the impact caused thereby will distort the net and exert a pull on the projectile which is resisted by the open canopy 27. The resistance thus caused will be sufficient to retard the torpedo especially as in all probability all of the canopies will act in this capacity and when the torpedo has been retarded, the spring 29 on at least one of the projectiles will be brought into use and impart the necessary thrust to the plunger and cause the same to fire the charge by driving the trigger or finger 31 through the cap 20 100 thus impaling the same with the cavity 22 of the plunger bridged by the said finger or trigger 31, thus destroying the torpedo or at least its propelling means.

From the above, it will be seen that not 105 only with this arrangement may the torpedo be successfully captured but it may also be destroyed which is a decided improvement over previously known torpedo guards.

Having thus described my invention, what 110 I claim as new and desire to secure by Letters Patent is:

1. A marine net comprising a net work, adapted to be wound upon a drum with one end attached thereto, a plurality of projectiles at spaced intervals along the free end of the net, and means for projecting said projectiles to cast the net and vertically submerge the same.

2. A marine net comprising a net work, 120 adapted to be wound upon a drum with one end attached thereto, a plurality of projectiles at spaced intervals along the free end of the net, and means for projecting said projectiles to cast the net and vertically submerge the same, said projectiles constructed to contain an explosive charge to be fired by the impact of an object with the net.

3. In a device of the class described, a marine net, a drum to which one end of the 130

net is attached and upon which the net is wound, a plurality of projectiles at spaced intervals along the free end of the net, and means for simultaneously and collectively projecting the said projectiles with a common trajectory for casting the net in a sheet-like form, said projectiles adapted to vertically submerge the net.

4. In a device of the class described, and as set forth in claim 3 and in which the projectiles are constructed to contain explosive charges with means for firing the same upon impact of an object with the net.

5. In a marine net, a net work, a float on one end thereof, a plurality of projectiles at spaced intervals along the opposite end, and means for collectively and simultaneously projecting the projectiles with a common trajectory for casting the net, said projectiles adapted to vertically submerge the net.

6. In a marine net, a net work, a float on one end thereof, a plurality of projectiles at spaced intervals along the opposite end, and means for collectively and simultaneously projecting the projectiles with a common trajectory for casting the net, said projectiles adapted to vertically submerge

the net, and comprising explosive devices adapted to be fired by the impact of an object contacting with the net.

7. In a marine net as set forth in claim 5 and in which the projectiles comprise explosive devices each of which having a normally inactive firing device, and means for rendering each firing device active to cooperate with the net in singularly or collectively firing the explosive devices by the impact of an object with the net.

8. In combination with a marine net, an explosive device comprising an explosive charge containing chamber, means for firing said explosive charge upon the impact of an object with the net comprising a plunger having a direct attachment to the net, a firing device with which the plunger co-acts in firing the charge, a canopy on the device adapted to resist movement of the explosive device in a direction toward the net, and a spring behind the plunger adapted to be compressed by the action of said canopy and expanded to force the plunger against the firing device when the pull on the means attaching the plunger to the net is relieved.

ERNEST KOHLER.
